UNITED STATES PATENT OFFICE.

GEORGE HARRIS, OF VERMILION, SOUTH DAKOTA.

MATCH-SAFE.

No. 887,937.

Specification of Letters Patent.

Patented May 19, 1908.

Application filed April 4, 1907. Serial No. 366,418.

To all whom it may concern:

Be it known that I, GEORGE HARRIS, a citizen of the United States, residing at Vermilion, in the county of Clay and State of South Dakota, have invented certain new and useful Improvements in a Match-Safe; and I do declare the following to be a full, clear, and exact description of the invention, such as will enable others skilled in the art 10 to which it appertains to make and use the same.

This invention relates to improvements in match safes.

The object of the invention is to provide 15 a match safe or holder adapted to be operated in such a manner as to permit a discharge or delivery of one match at a time, the arrangement being such that the delivered match will drop into the hand of the operator when discharged from the box.

With this object in view, the invention 20 consists of certain novel features of construction and combination of parts as will be more fully described and particularly 25 pointed out in the appended claims.

In the accompanying drawings, Figure 1 is 30 a perspective view of the match safe constructed in accordance with the invention; Fig. 2 is a vertical sectional view of the same, showing the parts in their closed or normal positions; and Fig. 3 is a similar view, showing the inner box or receptacle arranged to 35 permit of the discharge of a match, the latter being shown in dotted lines in the discharge groove, or recess of the box.

Referring more particularly to the drawings, 1 denotes the outer box or casing of the safe, said casing being here shown, and is preferably, rectangular in form and consists 40 of front and rear walls, 2 and 3, and end walls, 4. The casing at its upper end is provided with a suitable top or cover, 5. The front wall 2 extends a slight distance below the end wall, as shown at 6, and in said front 45 wall, immediately above the extension, 6, is formed a horizontally disposed match receiving groove, or recess, 7, said recess being of such size as to contain but one match.

Slidably mounted in the casing 1 is an 50 inner box or match receptacle, 8, said box consisting of a rear wall, 9, end walls, 10, and a downwardly and forwardly inclined bottom wall, 12. The front wall of the inner box 8 is formed by the front wall of the casing 1. The inner box or receptacle 8, when

in its normal position, is supported in the casing 1, by means of inclined cleats, 13, arranged on the inner side of the end walls of the casing 1, as shown. When the box or receptacle 8 is in its lower or normal position, 60 the forward edge of the bottom 12 engages the lower corner of the recess 7, whereby the matches contained in said box or receptacle will be directed toward the recess by the inclined bottom of said box so that when the 65 latter is in its normal position, one match will always be in place in said recess. The outwardly curved wall of the groove or recess 7 is preferably provided with a series of slots or openings, by means of which the contents 70 of the safe may be observed and the box refilled when necessary.

In operating the safe to obtain a match therefrom, the fingers are placed beneath the casing 1 into engagement with the inclined 75 bottom of the box or receptacle 8 and said receptacle pushed upwardly until the forward edge of the inclined bottom thereof clears the groove or recess 7, and the match contained therein. When the recess 7 has thus been 80 cleared by the movement of the box 8, the match contained in said recess will be permitted to roll out of the same and drop into the hand of the operator when pushing the box upwardly. The upward movement of 85 the box or receptacle 8 is limited by means of a stop lug, 14, arranged in the inner side of the rear wall of the casing 1, as shown.

From the foregoing description, taken in connection with the accompanying drawings, 90 the construction and operation of the invention may be readily understood without requiring a more extended explanation.

Various changes in the form, proportions 95 and the minor details of construction may be resorted to without departing from the principle or sacrificing any of the advantages of this invention, as defined in the appended claims.

Having thus described my invention, what 100 I claim as new, and desire to secure by Letters-Patent, is:

In a single delivery match safe, a casing 105 consisting of front, rear and end walls and a cover, the front wall of the casing being provided at a point remote from the normally lower open end of the latter with a match-receiving recess, a match receptacle arranged for endwise movement in the casing and consisting as a whole of a rear and end walls and 110

a downwardly and forwardly inclined bottom, the front edge of said bottom being disposed normally to bear on the front wall of the casing at a point immediately beneath said recess, inclined cleats attached to the end walls of the casing for supporting the receptacle in normal position, the receptacle being adapted for positive movement to permit the discharge of a match from the recess, and a stop

provided in the casing for limiting the upward movement of the receptacle.

In testimony whereof I have hereunto set my hand in presence of two subscribing witnesses.

GEORGE HARRIS.
